Inventors,

Henry B. Newhall,

Ernest F. Smith,

By their attorney, Harold D. Penney

UNITED STATES PATENT OFFICE

HENRY B. NEWHALL, OF PLAINFIELD, NEW JERSEY, AND ERNEST F. SMITH, OF QUEENS, NEW YORK; SAID SMITH ASSIGNOR TO NEW JERSEY FOUNDRY & MACHINE COMPANY, A CORPORATION OF NEW JERSEY.

SAFETY DEVICE FOR ELECTRIC BRIDGE CRANES.

Application filed March 21, 1924. Serial No. 700,918.

To all whom it may concern:

Be it known that we, HENRY B. NEWHALL and ERNEST F. SMITH, citizens of the United States, and residents of 1277 Woodland Ave., 5 city of Plainfield, county of Union, and State of New Jersey, and 8912 116th Street, Queens, county of Queens, and State of New York, respectively, have invented certain new and useful Improvements in Safety Devices 10 for Electric Bridge Cranes, of which the following is a specification.

This invention relates to safety devices for electric bridge cranes carrying trolleys movable therefrom to transfer beams, though 15 it is noted that the invention is not necessarily limited to cranes of this type, nor in some respects even to cranes.

One object of the invention is to provide an apparatus or device of this kind in which 20 the crane will not move unless the trolley is on it.

Another object of the invention is to provide an apparatus or device of this kind in which the trolley will not run off a transfer 25 beam unless a crane is ready to receive it, that is, the trolley will not run off the open end of a transfer beam.

Another object of the invention is to provide an apparatus of the above kind in 30 which emergency means are provided for moving the trolley from near the open end of a transfer beam.

Other objects of the invention are to improve generally the simplicity and efficiency 35 of such devices and to provide a device or apparatus of this kind which is durable, economical to manufacture and operate and which will not get out of order.

Still other objects of the invention will 40 appear as the description proceeds; and while herein details of the invention are described, the invention is not limited to these since many and various changes may be made without departing from the scope of 45 the invention as claimed.

The inventive features for the accomplishment 50 of these and other objects are shown herein in connection with an improved crane and transfer spur system which, briefly stated, includes a bridge crane with a trolley 55 there adapted to move from the crane to transfer beams. Means are provided whereby the crane is prevented from moving unless the trolley is thereon, and whereby the

trolley is prevented from moving off the end 55 of the transfer beam unless the crane is there to receive it.

In the accompanying drawing, showing by way of example, one of many possible 60 embodiments of the invention—

Fig. 1 is a diagrammatic plan showing the system, and

Fig. 2 is an elevation, partly in section, showing the side of the bridge, trolley and 65 transfer beam.

Our safety device is shown in combination with a traveling bridge crane including a bridge beam 10 and trucks 12 carrying wheels 14 running on track beams 15. A pair of collectors 17 and 18 on the bridge engage a 70 pair of main conductors 19 and 20 from any suitable source of current G. A motor 21 connected by gears 22 with one of the wheels 14 for driving said crane is provided with conductors 23, 24 and 25 for connecting said 75 motor with said contactors. A circuit breaker or opener interposed in said conductor 24, 25 includes a pair of parallel conductor bars 28 and 27 respectively mounted longitudinally on the bridge. A shoe 30 fast on a trolley 31 movable longitudinally on the bridge engages between said bars to connect the latter when the trolley is on the bridge and to break the circuit when the trolley leaves the bridge so the motor cannot 80 be operated or the bridge moved unless a trolley is thereon.

Conductor members 34 and 35 longitudinally mounted on the bridge and connected by jumpers 36 and 37 to said collectors are engaged by collector contacts 38, 39 of a motor 40 on the trolley for driving the trolley. Transfer beams 42 disposed laterally of the main trackway receive the trolley from the bridge; and a pair of fixed conductors 44 and 45 mounted parallel and near the transfer beams are alinable with said conductor members 34 and 35 when the bridge is alined with the transfer beam. One of said fixed conductors 45 includes a main live section 46 and a dead section 47 separated from the live section by an insulator 48. A jumper 50, 51 connecting said dead section with said live section has interposed therein a circuit closer or breaker comprising a pair of fixed shoes 52 and 53 connected to the members 50, 51 of the jumper, and a movable piece 100

55 mounted on a bracket 56 on the truck 13 and engaging and electrically connecting said shoes when the bridge is alined with the transfer beam. An emergency jumper 5 57, 58 connecting said sections 46, 47 has an emergency switch 60 interposed therein whereby said dead section 47 may be electrified at will.

10 It is, of course, understood that there may be many transfer beams along the line of the crane runway; and, as is often the case, they may form loops, so the trolley may run off the crane and then around the loop to another transfer beam where no crane 15 would be at the time standing to receive it, and run off the open end were it not for the circuit being opened between the shoes 52 and 53. As the trolley may become turned around, the shoes 30 and 55 20 are duplicated on opposite sides of the trolley.

The system herein is designed for direct current. If alternating current is used, the various circuit breaker means may be provided for each conductor line.

We claim as our invention:

1. In combination, a travelling bridge crane; a pair of collectors thereon; a pair of main conductors engaged by said collectors; a motor for driving said crane; conductors for connecting said motor with said collectors; a trolley movable longitudinally of the bridge; a circuit breaker interposed in one of said conductors comprising a pair of parallel conductor bars respectively mounted longitudinally on the bridge, and a shoe fast on said trolley engaging between said bars to connect the latter when the trolley is on the bridge and 40 to break the circuit when the trolley leaves the bridge; and transfer beams disposed laterally of the crane runway or main track-way for receiving the trolley from the bridge.

45 2. In combination, a crane; a trolley; a transfer beam; electric drive means for the trolley; and automatic means for cutting off the current from the drive means for preventing the trolley from leaving the transfer beam when the crane is not in place to receive it.

3. In combination, a crane; a means for moving said crane; a trolley on the crane; transfer beams with which the crane may be alined; conductor members on said crane; a motor on the trolley provided with collector contacts engageable with said conductor members; fixed conductors near the transfer beams engageable by said contacts 60 and with which the conductor members are alinable; one of said fixed conductors including a main live section, and a dead section near the crane runway; and a circuit breaker connecting said dead end with said 65 main portion including a movable piece

mounted on the bridge for closing the circuit breaker when the bridge is alined with the transfer beam.

4. In combination, a crane; a means for moving said crane; a trolley on the crane; a device for rendering said moving means inoperative when the trolley leaves the bridge; transfer beams for receiving the trolley from the crane; a motor for moving the trolley; and a device for rendering the trolley motor inoperative when the trolley approaches the end of the transfer beam and the crane is not alined with the transfer beam.

5. In combination, a bridge crane; a motor for said crane; conductors for supplying current for said motor; conductor members longitudinally mounted on said bridge connected to said collectors; a trolley on the crane; a motor on the trolley 85 for driving the trolley provided with contacts engageable with said conductor members; transfer beams for receiving the trolley from the bridge; a pair of fixed conductors mounted parallel and near the transfer beams and alinable with said conductor members when the bridge is alined with the transfer beam; one of said fixed conductors including a main live section and a dead section; a jumper connecting said dead end with said main portion; a circuit closer interposed in said jumper comprising a pair of fixed shoes connected to the members of the jumper; and a movable piece mounted on the bridge, engaging and connecting said shoes when the bridge is alined with the transfer beam.

6. In combination, a crane; a trolley; a transfer beam; means for preventing the trolley from leaving the transfer beam 105 when the crane is not in line to receive it; and emergency means for at will supplying current to the trolley while near the end of the beam.

7. In combination, a crane; a motor for moving said crane; a trolley on the crane; transfer beams for receiving the trolley from the crane; conductor members on said bridge; means supplying current to said members; a motor on the trolley provided with collector contacts engageable with said conductor members; fixed conductors near the transfer beams engageable by said contacts; one of said fixed conductors including a main live section, and a dead section near the crane runway; a circuit closer connecting said dead end with said main portion including a movable piece mounted on the bridge for closing the circuit closer when the bridge is alined with the transfer beam; and emergency means whereby said dead section may be electrified.

8. In combination, a crane; a motor for moving said crane; a trolley on the crane; transfer beams for receiving the trolley 120

- from the crane; conductor members on said bridge; means supplying current to said members; a motor on the trolley provided with collector contacts engageable with said conductor members; fixed conductors near the transfer beams engageable by said contacts; one of said fixed conductors including a main live section, and a dead section near the crane runway; a circuit closer connecting said dead end with said main portion including a movable piece mounted on the bridge for closing the circuit closer when the bridge is alined with the transfer beam; an emergency jumper connecting said sections; and an emergency switch interposed therein whereby said dead section may be electrified at will.
9. In combination, a bridge crane; a motor for said crane; conductors for supplying current for said motor; a trolley on the crane; a circuit breaker interposed in one of said conductors crossed by the trolley when the trolley is on the bridge and adapted to break the circuit when the trolley leaves the bridge; transfer beams for receiving the trolley from the bridge; conductor members on said bridge; a motor on the trolley provided with collector contacts engageable with said conductor members; fixed conductors near the transfer beams engageable by said contacts; one of said fixed conductors including a main live section, and a dead section near the crane runway; a circuit closer connecting said dead end with said main portion including a movable piece mounted on the bridge for closing the circuit closer when the bridge is alined with the transfer beam; and emergency means whereby said dead section may be electrified.
10. In combination, a crane; a trolley thereon; and means including an electric conductor carried by the trolley for preventing movement of the crane when the trolley is not thereon.
11. In combination, a crane; a motor for said crane; a trolley on the crane; and conductors for supplying current for said motor; said conductors being in part carried by the trolley for cutting off said current when the trolley is not on the crane.
12. In combination, a crane; a means for moving said crane; a trolley on the crane; and a device including a member fixed on the trolley for rendering said means inoperative when the trolley leaves the bridge.
13. In combination, a beam; a trolley thereon for transporting loads; a motor for said trolley; and means automatically disabling the motor as the trolley nears the end of the beam.
14. In combination, a crane including a bridge beam; a trolley on the bridge beam; transfer beams for receiving the trolley from the bridge beam; a motor on the trolley provided with a contact; a fixed conductor including a live section and a dead section between the live section and the path of the crane, both sections being mounted near the transfer beam and engageable by said contact; and means for cutting off current from said dead section when the bridge beam is out of alinement with the transfer beam, and while current is on the live section.
15. In combination, a crane including a bridge beam; a trolley on the bridge beam; transfer beams for receiving the trolley from the bridge beam; a motor on the trolley provided with a contact; a fixed conductor including a live section and a dead section both mounted near the transfer beams and engageable by said contact, when the crane is on the transfer beam; conducting means whereby said dead section is fed with current from the live section; and means including a circuit breaker in said conducting means for cutting off current from the dead section when the crane is out of alinement with the transfer beam.
16. In combination, a crane including a bridge beam; a trolley on the bridge beam; a transfer beam for receiving the trolley from the bridge beam; a conductor member carried on said crane; means for supplying current to said conductor member; a motor on the trolley provided with a contact engageable with said conductor member; a fixed conductor including a live section separated from said conductor member mounted near the transfer beam and engageable by said contact when the crane is on the transfer beam; and means for rendering the motor inoperative when the bridge beam is out of alinement with the transfer beam.
17. In combination, a crane including a bridge beam; a trolley on the bridge beam; transfer beams for receiving the trolley from the bridge beam; a conductor member longitudinally mounted on said crane; means for supplying current to said member; a motor on the trolley provided with a contact engageable with said conductor member; a fixed conductor separate from said conductor member and including a live section and a dead section both mounted parallel and near the transfer beams and alinable with said conductor member, when the bridge beam is alined with the transfer beam; and means for cutting off current from the dead section while it is still supplied to said conductor member.

Signed at New York, in the county of New York and State of New York, this nineteenth day of March, A. D. 1924.

HENRY B. NEWHALL.
ERNEST F. SMITH.
